ABSTRACT OF THE DISCLOSURE

This bending machine, in several automated steps, brings a pivotal clamp down against the stock to hold the stock against an arcuate bending surface of a die, advances a stock locator up to the die to permit bends closely adjacent the locator, and moves a ram linearly past the die. The ram carries a roller which forms the stock over the die while avoiding the possibility of scratching the stock surface. The die overlaps a die plate in such a manner that the force exerted by the bending process cannot cause the die to slip forward.

This invention relates to a machine for forming bends in cylindrical stock such as rods and tubes.

This machine is designed to permit rapid and accurate automatic forming of stock and to be readily adjustable so that it may be economically used for low volume production runs. The machine features an adjustable stock locating arrangement which permits complete control of the axial location of the bend and of the plane of the bend. This machine additionally features a clamping arrangement which prevents movement of the end of the stock so that no force is transferred to the locating points during the bending process. The machine also features a die mounting arrangement which provides rapid interchangeability of different size dies. The die mounting arrangement has an overlocking construction to prevent die movement during the bending process. The controls of the machine are interlocked for safety of operation, the operating cycle being automatic through the clamping process, providing for manual actuation of the ram bending stroke, and providing automatic completion of the cycle.

The details as well as other objects and advantages of this invention are disclosed in the following description and in the drawings in which:

FIGURE 1 is a front elevational view of the bending machine illustrating the die, locator, and ram;

FIGURE 2 is a side elevational view along line 2—2 of FIGURE 1 additionally illustrating the clamp;

FIGURE 3 is an enlarged view of a portion of FIGURE 2 illustrating the disposition of the clamp before the bending operation;

FIGURE 4 is a view similar to FIGURE 3 illustrating the disposition of the clamp after the bending operation;

FIGURE 5 is an enlarged sectional view of the locator illustrating its mounting for radial adjustment and the switch which initiates automatic operation of the machine;

FIGURE 6 is a schematic diagram of the hydraulic circuit for the machine;

FIGURE 7 is a schematic diagram of the pneumatic circuit for the machine; and

FIGURE 8 is a schematic diagram of the electrical circuit for the machine.

Referring first to FIGURE 1, the machine 10 is illustrated as having a single bending stage. However, it will be appreciated that the machine is readily adaptable for additional stages of operation which may be similar to that herein described.

Machine 10 includes a base 12 which supports a die plate 14 and a die 16. A ram carriage 18 and a locator carriage 20 are also supported on base 12. As shown in greater detail in FIGURES 2 through 4, carriage 18 is guided on rods 21 and moves a ram 22 linearly past die 16. Ram 22 carries a roller 24 which engages and forces the stock 26 downwardly to form a bend over the arcuate bending surface of die 16. The rolling contact of roller 24 with the stock 26 prevents scuffing of the stock.

A clamp carriage 28 is also supported on the base 12. Carriage 28 is guided on rods 29 and advances a clamp 30 which is pivotally mounted by a pin 32. Clamp 30 has a pair of arcuate surfaces 34 and 36 which engage the stock 26 and hold it against the arcuate bending surface of die 16. As shown in FIGURE 4, as the stock 26 is bent over die 16, clamp 30 pivots to maintain a uniform clamping pressure on the stock. The arcuate contour of the surfaces 34 and 36 permits rolling contact of clamp 30 with the stock 26 and prevents marring of the finish on the stock.

Die 16 is secured to die plate 14 by a plurality of fasteners 38 and is thus readily removable so that another die of different radius may be quickly substituted. Die 16 is provided with an extension 40 which overlies the back portion 42 of die plate 14. Extension 40 and back portion 42 have cooperating surfaces which are angled, as indicated at 44, to prevent forward movement of die 16 under the force of the bending process.

The locator carriage 20 is axially positioned along its guide rod 46 to properly locate the place of the bend along the length of the stock 26. As shown in FIGURE 4, locator carriage 20 supports a rim 48 within which a locator 50 is positioned. Locator 50 may be rotated within rim 48 and secured in a desired position by an adjustment piece 52. The rotative position of locator 50 is indicated by the markings 54 shown in FIGURE 3 and may thus be accurately determined. A pair of indexing members 56 within locator 50 cooperate with notches 58 in the stock 26; alternatively, indexing members 56 may cooperate with notches in a collar (not shown) appropriately secured about the stock 26. By such an arrangement, the radial position of the stock 26 may be adjusted so that the bend is formed in a proper plane whenever compound bends are required in the stock.

It will be appreciated from an examination of FIGURE 3 that it would be difficult to place the stock 26 in locator 50 behind die 16 when the stock must be bent very close to the locator. For this reason, locator 50 is provided with a pneumatic advance mechanism 60 (see FIGURE 2) which advances the locator toward the die after the stock has been placed within the locator. The automatic operation of advance mechanism 60, as well as the automatic operation of the clamp and ram, is described with further reference to the hydraulic circuit of FIGURE 6, the pneumatic circuit of FIGURE 7 and the electrical circuit of FIGURE 8.

As shown in FIGURE 5, when the stock 26 is placed in the locator 50 it engages a button 62. The length of button 62 may be varied for different lengths of the stock 26. Button 62 closes a switch S1 which connects a solenoid SOL1 across a suitable voltage source V. Solenoid SOL1 operates a pneumatic valve 64 to direct air from an air pump to the chamber 66 at one side of a pneumatic piston 68. Piston 68 advances locator carriage 20 to bring locator 50 up to the die 16.

Switch S1 also energizes a control relay CR1 which then closes its interlocks 70, 72, and 74. As locator 50 advances, it closes a switch S2 which energizes a solenoid SOL2. Solenoid SOL2 operates a hydraulic valve 76 which directs hydraulic fluid, delivered by a pump P from a tank T, to a servo 78. Servo 78 operates a second hy-

draulic valve 80 to direct fluid to the chamber 82 at one side of a hydraulic piston 84. Piston 84 advances clamp carriage 28 causing clamp 30 to secure the stock 26 against die 16.

As piston 84 advances clamp 30, a switch S3 is opened from its A contacts and closed across its B contacts to energize a control relay CR2. Relay CR2 then closes its interlocks 86, 88, 90, 92, and 94 and opens its interlock 96. Interlock 88 closes a circuit to a pair of manual switches MS1 and MS2 which should be suitably disposed so that it is impossible for the machine operator to be in the way of the advancing ram 22. When the operator actuates switches MS1 and MS2, closing their C, D, E, and F contacts and opening their G and H contacts, a control relay CR3 is energized, closing its interlock 98 and opening its interlock 100. Interlock 98 energizes a solenoid SOL3 which operates a hydraulic valve 102. Valve 102 directs fluid to a servo 104 which operates another hydraulic valve 106. Valve 106 directs fluid to the chamber 108 at one side of a hydraulic piston 110. Piston 110 advances ram carriage 18 causing ram 22 to bend the stock 26 over the die 16.

A stop 112 is positioned on a portion of the ram mechanism to engage a switch S4 when the stock 26 has been bent to a desired angle. Adjustment of stop 112 permits control of the angle to which the stock 26 is bent. When switch S4 is closed by stop 112, a control relay CR4 is energized to close its interlocks 114 and 120 and open its interlocks 116 and 118. Interlock 114 energizes a solenoid SOL4 to operate hydraulic valve 102 and direct fluid to servo 122. Servo 122 operates hydraulic valve 106 to direct fluid to a chamber 124 at the opposite side of piston 110. Piston 110 is thus re-energized to retract ram 22.

When ram 22 retracts, a switch S5 is opened from its J contacts and closed across its K contacts. Switch S5 thus energizes a control relay CR5 which closes its interlock 126. Interlock 126 energizes a solenoid SOL5 which operates pneumatic valve 64 to direct air to the chamber 128 at the opposite side of pneumatic piston 68. Piston 68 is thus re-energized to retract locator 50.

When locator 50 retracts, a switch S6 is closed to energize a solenoid SOL6. Solenoid SOL6 operates hydraulic valve 76 to direct fluid to a servo 130. Servo 130 operates hydraulic valve 80 to direct fluid to a chamber 132 at the opposite side of piston 84. Piston 84 is thus re-energized to retract clamp 30.

If it is necessary to suddenly retract clamp 30 before the end of the bending cycle, a manual switch MS3 is closed to energize a control relay CR6 which closes its interlocks 134 and 136 and opens its interlock 138. Interlock 136 energizes solenoid SOL6 which causes retraction of the clamp 30.

Timed relays TD1 and TD2 are provided which delay a predetermined period of time after energization before opening their interlocks 140 and 142 to de-energize control relays CR3 and CR5. Solenoids SOL3 and SOL5 thus remain energized only for the time necessary to operate valves 102 and 64.

A series of simultaneously operated selector switches SS is provided which, in the indicated position across the L contacts, allows automatic advance of locator 50. If automatic advance of locator 50 is not desired, selector switches SS are switched to the M contacts. The above-described electrical and hydraulic circuits will then operate in a similar manner but solenoids SOL1 and SOL5 will be inactive.

The above-described electrical circuit provides a completely interlocked control network in which the elements are energized only during the time a specific function is required. If the machine is operated incorrectly or fails to perform properly, further operation is prevented. This arrangement is provided to make operation of the machine as safe as possible.

From the foregoing, it will be appreciated that this machine is rapidly and easily adjusted to form stock into a desired configuration; that the die mounting arrangement and the clamp and ram operating modes provide accuracy in the forming operation; and that the forming operation is performed automatically and safely.

I claim:

1. A machine for forming bends in cylindrical stock comprising a stationary die having an arcuate bending portion, clamp means adapted to hold the stock to prevent sliding movement of the stock relative to the die, and ram means movable linearly relative to said die, said ram means including a roller adapted to engage the stock by rolling contact and form the stock about the arcuate bending portion of the die.

10 2. A machine for forming bends in cylindrical stock comprising a stationary die having an arcuate bending portion, clamp means adapted to hold the stock against said arcuate bending portion of said die to prevent sliding movement of the stock relative to the die, and ram means adapted to form the stock about the arcuate bending portion of the die, said clamp means including a clamping portion mounted on a pivot, said clamping portion rotating about said pivot to hold the stock against said die as the stock is formed about said die.

25 3. The machine of claim 2 wherein said clamping portion includes a pair of surfaces each adapted to engage the stock.

30 4. The machine of claim 3 wherein each of the stock-engaging surfaces on said clamping portion have an arcuate contour engaging the stock by rolling contact.

35 5. A machine for forming bends in cylindrical stock within a certain plane comprising a stationary die having a straight portion disposed within said plane for receiving the stock and having an arcuate portion disposed within said plane about which the stock is bent, ram means movable within said plane for applying force to the stock in a direction within said plane to thereby form the stock about said arcuate portion of said die, clamp means for holding a portion of the stock against said straight portion of said die and tending to prevent movement of that portion of the stock within said plane relative to said die whereby the force applied by said ram means is transferred through the stock to said straight portion of said die in directions both perpendicular and tangential to said straight portion, and a stationary die plate having a die supporting portion disposed in said plane and oriented in a direction for absorbing the force transferred to said die in directions both perpendicular and tangential to said straight portion of said die, said die having a portion supported by said die supporting portion of said die plate whereby force transferred to said die is transmitted to and absorbed by said die plate and whereby said die is prevented from moving relative to said die plate.

40 55 6. A machine for forming bends in cylindrical stock comprising a die having an arcuate bending portion, clamp means adapted to hold the stock to prevent sliding movement of the stock relative to the die, ram means adapted to form the stock about the arcuate bending portion of the die, and locating means adapted to surround the end of the stock to accurately position the stock upon said die, said locating means including automatic mechanism actuatable upon insertion of the stock to advance the stock up to said die whereby a bend may be formed in the stock closely adjacent said locating means.

60 7. The machine of claim 6 wherein said automatic mechanism comprises a first electrical switch operable upon insertion of the stock into said locating means to energize a pneumatic piston which thereupon advances said locating means a predetermined distance toward said die and wherein said machine further includes automatic sequencing mechanism comprising a second electrical switch operable upon predetermined advance of said locating means to energize a first hydraulic piston which thereupon advances said clamp means to hold the stock,

a manual control, a third electrical switch operable upon predetermined advance of said clamp means to energize said manual control, said manual control being operable to energize a second hydraulic piston which thereupon advances said ram means to form the stock about said die, a fourth electrical switch operable upon predetermined advance of said ram means to re-energize said second hydraulic piston which thereupon retracts said ram means, a fifth electrical switch operable upon retraction of said ram means to re-energize said pneumatic piston which thereupon retracts said locating means, and a sixth electrical switch operable upon retraction of said locating means to re-energize said first hydraulic piston which thereupon retracts said clamp means.

8. The machine of claim 6 which further includes a die plate having a back portion and wherein said die is mounted on said plate, said die having an extension overlying the back portion of said die plate to prevent move-

ment of said die relative to said die plate, wherein said clamp means includes a clamping portion mounted on a pivot, said clamping portion rotating about said pivot to hold the stock against the face of said die and prevent sliding movement of the stock relative to said die, and wherein said ram means is movable linearly relative to said die and includes a roller adapted to engage the stock by rolling contact to form the stock about the arcuate bending portion of the die.
